METHOD AND RESULTING COMPOUND
FROM ADMIXING SODIUM MORRHUATE
AND QUININE SOLUTIONS

Frederick R. Greenbaum, Philadelphia, Pa.

No Drawing. Application April 18, 1935,
Serial No. 17,059

6 Claims. (Cl. 167—67)

The object of this invention is to provide a satisfactory clear stable solution of sodium morrhuate and quinine under commercial conditions, such mixture being free from any precipitate, and to provide an improved process for mixing said substances, this application being a continuation in part of Serial No. 722,401, filed April 25, 1934.

A further and more specific object is to provide a product comprising the mixture of sodium morrhuate and quinine. Benzyl alcohol may be used as a local anesthetic and preservative.

A further object is to provide a modified process, which results in a slightly modified product, comprising the combination of sodium morrhuate, quinine alkaloid and normal sodium hydroxide.

It is well known that in the obliterative treatment of varicose veins by means of injections, the solutions that have been used until my work upon the subject have been sodium morrhuate, and quinine urea hydrochloride, or quinine-urethane, in each case such specifics being used singly and independently. Of these, quinine urea hydrochloride and quinine-urethane are water-soluble salts, either hydrochloride or sulphate, and are not the free alkaloid. Therefore, as many patients are quinine idiosyncratic, the use of quinine solutions has frequently heretofore not been permissible, altho the thrombosis or obliteration where quinine solutions can be used is firmer and more resistant than with sodium morrhuate.

On the other hand, many patients will not obliterate with five percent (5%) or even ten percent (10%) sodium morrhuate, nor do they respond at all to quinine solutions, aside from the question of idiosyncrasy. Consequently, there has long been a definite need for a solution in which might be combined the advantages of both of these substances, but free from the disadvantages of either as related to any particular type of patients, or in other words a solution which would be completely effective with consistent uniformity, with all patients and it is such a solution that has been devised and is hereinafter described in detail.

Extensive clinical experience, with this combined sodium morrhuate and quinine in five percent (5%) and ten percent (10%) solutions, proves that the addition of a proper amount of quinine alkaloid markedly increases the obliterative action of sodium morrhuate. The presence of sodium morrhuate in combination with the quinine alkaloid appears to eliminate the quinine idiosyncrasy experienced with many patients, permitting a firmer and more resistant sclerosis

than that produced by quinine salts or by sodium morrhuate used separately.

Various authorities in the treatment of varicose veins report the combined solution of sodium morrhuate and quinine alkaloid is markedly superior to either of these substances employed singly, by giving a much higher percentage of uniformly desirable results, than can be obtained from the use of sodium morrhuate or quinine salts solutions used individually. In fact, very few unfavorable reactions have been reported to date.

The two substances applied in the same solution are effective as sclerosing agents, and as a result of their combination have the advantage of (a) producing positive and firm sclerosis, (b) rarely producing cramps even to the slightest degree, (c) causing no pain whatsoever, (d) requiring but relatively small dosage, (e) being characterized by low viscosity, (f) being non-toxic, and (g) causing no slough when extravasation occurs, while (h) reactions caused by sodium morrhuate or any quinine appear to be negative or at most slight. Following within a few minutes after injection is made, the vein begins to harden and such hardening usually extends from two to four inches below the point of injection, depending upon the quantity used, the size of the vein, and the individual susceptibility of the particular vein to the treatment. Within twenty-four hours the vein usually becomes hard and firm.

At first, in endeavoring to produce a solution of sodium morrhuate and quinine urethane or quinine urea hydrochloride, I realized that chemically it was considered an impossibility, as in these latter substances quinine hydrochloride is used, and as a result of the acid reaction of each of the salts (quinine urethane and quinine urea hydrochloride), a portion of the sodium morrhuate is neutralized, thereby precipitating the fatty acids of the latter, and producing a cloudy solution which is unfit for clinical use. As it was therefore evident that a novel method of combining the two substances had to be developed, I resorted to quinine alkaloid, which being of a relatively weak basic nature is compatible with, and will very slowly dissolve to the extent of about two percent (2%) in, a hot five to ten percent (5%-10%) solution of sodium morrhuate, the quinine alkaloid being even less soluble in said solution when cold.

This method of mixing the quinine alkaloid with the sodium morrhuate, however, is far too slow for commercial purposes, besides the fact that while the quinine alkaloid is retained in solution, the free alkaloid may be precipitated, there-

by making the resulting solution unsuited for clinical use. Consequently, two methods have been devised for satisfactorily dissolving and combining the quinine alkaloid and the sodium morrhuate in a resulting clear and stable solution. The first of these processes comprises the dissolving of both of said substances in heated benzyl alcohol, which latter substance contributes anesthetic characteristics to the resulting solution.

By way of example, the desired solution is obtained by this process, by dissolving twenty grams (20 grs.), of free alkaloid quinine in twenty cubic centimeters (20 cc.) of heated benzyl alcohol, after which this solution is added slowly and with constant stirring to one thousand cubic centimeters (1000 cc.) of a five per cent (5%) aqueous solution of sodium morrhuate, heated and maintained close to the boiling point. Gradually the alkaloid quinine and benzyl alcohol solution becomes dissolved in the sodium morrhuate solution, during the steady addition of one to the other and with constant mechanical stirring. Finally, a clear solution is obtained, which contains between five percent (5%) and ten percent (10%) of sodium morrhuate, two percent (2%) alkaloid quinine, and two percent (2%) benzyl alcohol.

Having produced the new mixture thus described, the benzyl alcohol may be then or at any time hereafter distilled off, so as to leave an equally clear mixture of the sodium morrhuate and quinine alkaloid alone, both for use as a simple mixture where such is desired, or as a commercial basis for still other mixtures and/or compounds with one more still further substances, depending upon what ultimate preparation or result is desired.

The other method hereinbefore referred to, and which is now preferred over the one just described, comprises the addition of quinine alkaloid to free fatty acids of cod liver oil while heated, it having been found that the former is readily soluble in the latter, and that the former also remains in the oily solution even after cooling, and totally without the slightest tendency to precipitate. Benzyl alcohol is then preferably added; not as a solvent as in the first-described process, but for its anesthetic and preservative function, altho the product may be made without the addition of benzyl alcohol, so that its presence in the final compound is desirable more as the result of its anesthetic than for its preservative value.

In this second process, by the addition of quinine to the free fatty acids (morrhuate acids) of cod liver oil, quinine morrhuate is directly formed, and when water is added to the quinine morrhuate, no separation or precipitation of the quinine alkaloid occurs. In order to obtain a clear solution, it is necessary to add normal sodium hydroxide, by heating and stirring. When the pH value of the resulting solution is between 8 and 10, a clear, stable solution is obtained, containing five percent (5%) sodium morrhuate or six percent (6%), two percent (2%) alkaloidal quinine, and two percent (2%) benzyl alcohol. The sodium hydroxide performs the function of transforming the quinine morrhuate into sodium morrhuate and quinine. Alkaloidal quinine is not soluble in an alkaline solution, but in this process of preparing the quinine morrhuate, it remains in colloidal solution, due to the dispersoid action of sodium morrhuate (cod liver oil soap) and possesses the property of holding in alkaline

solution such substances as are otherwise insoluble therein.

Ordinarily in making quinine solutions acid salts are used because quinine is only soluble in water in acid condition. Acid solutions of quinine cannot be injected into the body tissues without producing severe necrosis, wherefore it is entirely unsuited for the treatment of varicosities. By comparison, the product resulting from each of the processes hereinbefore described is both alkaline and holds the quinine permanently in a clear solution. When injected into the veins, no necrosis occurs as hereinbefore stated, and so far as is known no similar alkaline solution has previously been produced.

Furthermore, it has also been discovered that instead of using the free fatty acids of cod liver oil, the free fatty acids of olive oil, oleic acid, cotton seed oil, castor oil, and other vegetable and animal oils, may be used with equal facility, and that all of the known fatty acids will when heated dissolve the quinine alkaloid and form an oily solution. If such oily solution is poured into water and simultaneously stirred and heated, no separation of the quinine alkaloid occurs and the oily layers remain unchanged. If, however, normal sodium hydroxide is added, the sodium soap of the fatty acid is formed, such for instance as sodium oleate or the sodium salts of the fatty acids of olive, or of cotton seed, of castor oil, or of vegetable or animal oils, each and all of which possesses the property of maintaining the quinine alkaloid in colloidal solution.

Finally, it may be said in brief summary, that the sclerosing action of the sodium morrhuate and quinine in combination is greatly enhanced, over the use of either of them independently of the other, and that this improved result is due to the new and original use of the sodium salts of the fatty acid complex of animal and vegetable oils combined with quinine alkaloid. Furthermore, while the use of sodium morrhuate alone produces reactions in approximately three percent (3%) of the many cases observed, and the independent use of quinine has a similar effect in about one percent (1%) of such cases, the use of the two substances in one and the same solution does not produce the quinine reactions nor the sodium morrhuate reaction sometimes encountered. It seems that the alkaloidal quinine in colloidal dispersion in the sodium morrhuate (cod liver oil soap) solution does not possess the undesirable properties of the crystallloid quinine, which is contained in true solutions of quinine urea hydrochloride or quinine urethane.

Having thus described my invention what I claim as new and desire to secure by Letters Patent is:—

1. The process of producing a solution of quinine alkaloid and sodium morrhuate, which consists in dissolving quinine alkaloid in morrhuate acid, to produce quinine morrhuate, and then dissolving the quinine morrhuate in normal sodium hydroxide.

2. The process of producing a solution of quinine alkaloid and sodium salts of the fatty acid of a vegetable or animal oil, which consists in dissolving quinine alkaloid in the acid of a vegetable or animal oil, to produce quinine fatty acid complexes and then dissolving the quinine fatty acid complexes in normal sodium hydroxide.

3. The process of producing a solution of quinine alkaloid and sodium morrhuate, which consists in dissolving quinine alkaloid in a morrhuate acid to produce quinine morrhuate, and then dis-

solving the quinine morrhuate in normal sodium hydroxide until the pH value is between 8 and 10 to produce a clear stable solution.

4. The process of producing a solution of quinine alkaloid and sodium salts of fatty acids, which consists in dissolving quinine alkaloid in the fatty acid of a vegetable or animal oil, to produce quinine fatty acid complexes, and then dissolving the quinine fatty acid complexes in normal sodium hydroxide until the pH value is between 8 and 10, to produce a clear stable solution.

5. The process of producing a solution of quinine alkaloid and sodium morrhuate, which consists in dissolving quinine alkaloid in a morrhuate

acid to produce quinine morrhuate, adding benzyl alcohol, and finally adding normal sodium hydroxide until a pH value of 8 to 10 is reached, to produce a clear stable solution.

6. The process of producing a solution of quinine alkaloid and sodium salts of fatty acids, which consists in dissolving quinine alkaloid in the free fatty acid of a vegetable or animal oil, to produce quinine fatty acid complexes, adding benzyl alcohol and finally adding normal sodium hydroxide until a pH value of 8 to 10 is reached, to produce a clear and stable solution.

FREDERICK R. GREENBAUM.

CERTIFICATE OF CORRECTION.

Patent No. 2,046,116.

June 30, 1936.

FREDERICK R. GREENBAUM.

It is hereby certified that error appears in the printed specification of the above numbered patent requiring correction as follows: Page 2, first column, line 5, for the word "table" read stable; and that the said Letters Patent should be read with this correction therein that the same may conform to the record of the case in the Patent Office.

Signed and sealed this 22nd day of September, A. D. 1936.

Henry Van Arsdale
